RUSSELL HUFF, OF DETROIT, MICHIGAN, ASSIGNOR TO DODGE BROTHERS, OF DETROIT,
MICHIGAN, A CORPORATION OF MICHIGAN.

PRIMING-CUP.

1,288,003.

Specification of Letters Patent.

Patented Dec. 17, 1918.

Application filed June 1, 1917. Serial No. 172,149.

To all whom it may concern:

Be it known that I, RUSSELL HUFF, a citizen of the United States, residing at Detroit, Michigan, have invented certain new and useful Improvements in Priming-Cups, of which the following is a clear, full, and exact description.

This invention relates to a priming cup for use in the cylinders of internal combustion engines or for other similar purposes.

One object of the invention is to provide a priming cup which is of good appearance and is easily manufactured.

Another object of the invention is to provide a priming cup which can be made from stock which is of such dimensions as to be inexpensive.

Still another object is to provide a priming cup so constructed that the amount of material removed from the stock in manufacturing it is a minimum and, consequently, the cost of machining and also of the material is a minimum.

These being among the objects of the present invention, the same consists of certain features of construction and combinations of parts to be hereinafter described and then claimed with reference to the accompanying drawings which illustrate a suitable embodiment of the invention having the above and other objects in view.

Figure 1 is an elevation of the improved priming cup.

Fig. 2 is a plan view of the same.

Fig. 3 is a vertical sectional view through the priming cup showing the valve seated.

Fig. 4 is a similar view showing the valve raised from its seat.

Fig. 5 is a sectional elevation of the stem 40 of the cup before it is united with the cup proper.

Fig. 6 is an elevation partly in section showing the valve.

Fig. 7 is a vertical elevation of the valve 45 taken at right angles to Fig. 6.

Fig. 8 is a cross section taken on the line 8-8 of Fig. 7.

Referring to Fig. 3, the priming cup is seen to consist of a body composed of the cup 10 and stem 11 in the latter of which the valve 12 is threaded. The cup 10 is stamped from sheet metal and is united to the stem 11 by spinning over the thin cylindrical extension 13 of the latter, so as to grip the bottom of the cup firmly, the shape of the stem

before the spinning operation being shown in Fig. 5. The operation of turning over this cylindrical extension to grip the cup may, of course, be performed by the use of suitable dies if this method is preferred to spinning.

The exterior of the stem 11 is threaded, preferably with a standard pipe thread, so that it may be screwed into a cylinder casting or other support and may also be provided with a portion of hexagonal section to facilitate the application of a wrench. This hexagonal section is provided by making the stem from hexagonal stock. Along the axis of the stem is a cylindrical hole, 70 threaded through the greater part of its length to receive the valve 12 and provided with a conical seat 14 for said valve near its lower end. The valve 12 is made from a piece of round stock preferably of brass or other non-corrosive metal. This stock is threaded near one end and has the other end bent at right angles with the threaded part and flattened to form a suitable handle which projects laterally beyond the edge of 80 the cup. In order to provide a passage past the valve when it is raised from its seat, longitudinal grooves 15 are cut in the threaded portion.

An examination of the drawings will 85 show that the amount of material to be removed from the stock used in the manufacture of this improved cup is very small. The cup 10 being made from sheet metal can be manufactured with very little waste 90 and the stem 11, if made from hexagonal rolled stock, requires the removal of only a small amount of material. Moreover, the valve 12, being made from round stock which is flattened at one end to form a handle and bent as shown in the drawing can be manufactured practically without waste, particularly if the threads are produced by a rolling process. The stock which would be required if the same cup was turned from 100 a solid bar would, of course, be at least as great in diameter as the upper end of the cup and a large amount of material would have to be removed, both from the exterior and from the interior of the body. With a 105 cup machined from solid stock, it would also be necessary to mill wrench engaging surfaces, an expensive operation which is entirely eliminated in the construction herein described.

2

It is obvious that the invention is susceptible of further modification as parts may be omitted, parts added and parts substituted without departing from the spirit and scope of the invention as expressed in the claims.

5 What I claim as new is:

1. A priming cup, comprising a stem having a bore screw-threaded in its outer portion and formed with an outwardly presented conical valve seat the larger end of which is approximately the diameter of said bore, located between said thread and the lower extremity of said stem, a cup mounted on the upper end of said stem around said bore, and a valve having a conical seating surface at its lower end, said valve having a screw-thread engaged with the screw-threaded portion of said bore, and the body of said valve, exclusive of its said screw-thread and the said seating surface, being of approximately the same diameter throughout, and one of the screw threaded members of said screw connected parts having a groove leading from said cup to said 10 valve seat.
2. A priming cup, comprising a stem having a bore screw-threaded for a portion of its length in its outer end, a thin cylindrical extension from the outer end of said threaded portion, said stem having a wrench receiving head about said threaded portion, and the portion of said bore below said threaded portion having an outwardly presented conical valve-seat, a frusto-conical sheet metal cup having a bottom opening 15 into which said cylindrical extension fits, the said extension being turned over upon the bottom of said cup, the base of said cup be-

ing of slightly greater width than said wrench-head, and an exteriorly threaded 40 valve having a conical seating surface at its inner end, said valve being screwed into the screw threaded portion of said bore, and one of the screw-threaded members of said screw connected parts having a groove leading 45 from said cup to said valve seat.

3. A priming cup, comprising an exteriorly screw-threaded stem having a bore screw-threaded for a portion of its length in its outer end, a portion of said bore being 50 formed with a conical valve-seat the larger end of which is approximately the diameter of said bore, located intermediately of the length of the exteriorly screw-threaded portion of said stem so that the lower spirals 55 of the interior screw-thread are disposed within the upper spirals of the exterior screw-thread, a wrench receiving head about the upper threads of said interior screw-thread, and a valve having a conical seating surface at its inner end, said valve having a screw-thread engaged with the screw-threaded portion of said bore, and the body of said valve, exclusive of its said screw-thread and the said seating surface, being of approximately the same diameter throughout, one of the said screw-thread connected members having a longitudinal groove leading 60 from the top of said bore to said valve seat.

Signed at Detroit, Mich., this 29th day of May, 1917.

RUSSELL HUFF.
